UNITED STATES PATENT OFFICE.

HARRY Y. ARMSTRONG, OF SYRACUSE, NEW YORK, ASSIGNOR OF ONE-HALF TO
WILLIAM L. HALL, OF CHICAGO, ILLINOIS.

WRAPPING-MACHINE.

1,400,202.

Specification of Letters Patent. Patented Dec. 13, 1921.

Application filed April 26, 1920. Serial No. 376,729.

To all whom it may concern:

Be it known that I, HARRY Y. ARMSTRONG, a citizen of the United States, and a resident of Syracuse, in the county of Onondaga and 5 State of New York, have invented certain new and useful Improvements in Wrapping-Machines; and I do hereby declare that the following is a full, clear, and exact description thereof, reference being had to the accompanying drawings, and to the characters 10 of reference marked thereon, which form a part of this specification.

This invention relates to wrapping machines of that kind which is capable of taking the article to be wrapped, as a stick of chewing gum, and inclosing it in an inner wrapper, and an outer label wrapper, and sealing the latter wrapper and passing the articles so wrapped into an accumulating device, from which groups of a predetermined 20 number are adapted to be extracted for further treatment, as, for instance, inclosed in a sealed group wrapper and a label group wrapper, if desired.

25 The invention has for its objects the production of an exceedingly simple and effective construction for thus wrapping the articles, so constructed and arranged as to effect the several folds of the wrapper to 30 produce individually wrapped sticks by the use of simple, readily operable, rugged, and durable mechanisms, and of a character whereby the machine has large output capacity by the use of mechanisms that are 35 adapted to operate at relatively slow speed and short operative strokes, whereby the machine runs smoothly and without jars or vibrations characteristic of known so-called high production machines, thereby avoiding 40 the racking effect of excessive vibration heretofore observed in high production machines.

A further object of the invention is to provide a novel mechanism for causing the 45 articles to pass through the machine while being wrapped, designed to avoid severe handling of the articles and wrappers and thereby breakage thereof, with consequent clogging of the machine, a feature which 50 adapts the machine to continuous operation and saving losses of time in keeping the machine clear of clogging impediments, as broken articles, torn paper, and the like.

55 Another object of the invention is to provide an improved mechanism for advancing

the articles, such as sticks of chewing gum, whereby the articles are not subject to severe impacts or urging parts, which tends to crush soft articles or break dry and more or less fragile articles.

60 Another object of the invention is to provide, in connection with a reciprocable carriage means, an intermittently swingable or otherwise movable stop element, the function of which is to hold or arrest the articles 65 when the carriage is traveling in one direction so as to cause the articles to be displaced in and relatively to the carriage in such direction that when the stop element is released from the article holding position, the 70 articles travel bodily with the carriage in the reverse direction and are thereby advanced through the machine and relative to wrapping mechanisms by which the articles 75 are wrapped.

Another object of the invention is to provide, in a wrapping machine of the character described, a reciprocable carriage, having thereon and movable therewith a rotative folding element to receive articles and 80 their wrappers to partially fold the wrappers about the articles during the reciprocable and turning movements of the carriage and folding element, respectively.

85 A further object of the invention is to provide, in combination with such reciprocable carriage and rotative folding element, stationary folding means to partially effect wrapping of the articles, together with means coöperable with the reciprocable carriage, to intermittently displace the articles rearwardly and through the stationary folding means and to release the wrapped articles from the carriage.

90 A further object of the invention is to 95 provide novel means of transferring the articles from a stack thereof in a swinging or movable magazine to the wrapping mechanism, constructed an operating to effect such transfer by a relative total movement 100 of the bottommost article of the stack, and by means which do not tend to break or abraid the articles; and, further, to correlate a wrapper feed with such swinging or movable magazine that coöperates therewith to delicately urge the articles against a wrapper deposited in the transfer plane of the articles and into the folding mechanism without danger of displacing the wrapper or 105 tearing it.

A further object of the invention is to provide a novel wrapper cutting and feed device for coöperation with a swinging or movable article magazine or holder.

- 5 A further object of the invention is to provide a swinging or moving magazine in which to store the articles in a stack, with means to release the bottommost article from the stack in such a way that the stack 10 is at all times supported by means at the magazine bottom which constitutes fixed means to release the articles from the bottom of the stack when the magazine is swinging or moved to and fro in its limited 15 path.

The invention has as other objects to provide means to correlate and operate the mechanisms above set forth, to give proper combinative effect thereto in a unitary machine, and the invention consists in the combination and arrangement of the parts shown in the drawings and described in the specification, and is pointed out in the appended claims.

25 In said drawings:

Figure 1 is a side elevation of a machine embodying my invention.

Fig. 2 is a front elevation thereof.

30 Fig. 3 is a plan view with parts in section.

Fig. 4 is an enlarged side elevation of the front end of the machine, showing more particularly the gum magazine and wrapper feeding and cutting mechanism.

35 Fig. 5 is a sectional view taken on line 5-5 of Fig. 1.

Fig. 6 is an enlarged plan section on line 6-6 of Fig. 1, with parts omitted.

40 Fig. 7 is a vertical section on line 7-7 of Fig. 6 showing the driving mechanism for the folder shafts.

Fig. 8 is a transverse vertical section on line 8-8 of Fig. 3 showing a portion of its slide bearings and a portion of the folding mechanism therewith.

45 Fig. 9 is a perspective view of a portion of the inner wrapper folding element.

Fig. 10 is a transverse vertical section on line 10-10 of Fig. 3, through another 50 portion of the carriage and frame.

Fig. 11 is a perspective view of a wrapping folding plate employed in the machine.

55 Fig. 12 is a perspective view of a paste pot mechanism and its paste applying mechanism.

Fig. 13 is a transverse vertical section on line 13-13 of Fig. 3 through another portion of the carriage and frame.

60 Fig. 14 is a perspective view of a hinged stop element that coöperates with the reciprocating carriage to change the position of the gum stick and wrappers relatively to the carriage.

65 Fig. 15 is a section on line 15-15 of Fig. 3 looking forwardly.

Figs. 16, 17, and 18 are sectional views taken on line 16-16 showing the mechanism in changed positions.

Figs. 19 and 20 are enlarged sections of the lower and coöperating parts of the gum 70 releasing and inner wrapper folding element.

Fig. 20^a (sheet 3) is a plan fragmentary detail of the wrapper cutting mechanism:

Figs. 21, 22, and 23 are diagrammatic 75 views illustrating the coöperating of the stop element with the inner wrapper folding element.

Fig. 24 is an enlarged perspective fragmentary view of the folding plate shown 80 in Fig. 11.

Fig. 25 is a detail section on the line 25-25 of Fig. 3.

Fig. 26 is a perspective view of a stick of chewing gum inclosed in an inner 85 wrapper.

Fig. 27 illustrates the presentation of a wrapped single stick to an outer or label wrapper.

Figs. 28 and 29 show progressive steps of 90 applying the said label wrapper to wrapped gum stick.

Fig. 30 is a perspective view of a group of gum sticks in readiness for sealing.

The invention is herein illustrated as applied to a machine for wrapping sticks of chewing gum and like articles, taking a single stick, progressively wrapping it in a suitable inner oiled or waxed wrapper W' cut from a strip of paper unrolled from a 100 reel and folding the same around the stick with its side flaps w, w, overlapping, and with the end flaps w' w' laid in, as best shown in Fig. 26, then wrapping said stick so wrapped in an outer or label wrapper 105 L, to which the initially wrapped sticks are presented, in the manner shown in Fig. 27, with paste patches applied to one side lap l', the label wrapper being progressively wrapped about the initially wrapped stick 110 in the manner shown in Figs. 28 and 29, and by the mechanism hereinafter described, the paste bearing side flap being pasted over the opposite side flap l² to complete the application of the label wrapper, with the ends 115 of the label wrapper extending over and confining the end flaps w'. The double wrapped sticks are thereafter brought together in the group containing a prescribed number of pieces, after which the group may subsequently be sealed or otherwise handled, depending upon the practice of the manufacturer.

The embodiment of the invention illustrated in the drawings contemplates the 125 utilization of a reciprocable carriage, one or more intermittently rotatable, side folding elements movable with the carriage which move or moves separately over the sticks, together with a wrapper or wrappers, fed 130

by suitable mechanism across the path or paths of the gum sticks, as they are released from the magazine, or other part of the mechanism, and a suitably constructed and 5 actuated stop element which co-operates with the reciprocable carriage to arrest the gum sticks in space so that they may be progressively advanced by movement of the carriage, the intermittently rotative element or 10 elements serving to side wrap the gum sticks and the side wrapped gum being passed through end flap folders that are fixed relatively to the carriage. If the gum sticks are to be wrapped in single wrappers, 15 as the wrappers W, shown in Fig. 26, but one rotative side folding mechanism movable with the carriage is used, into which the gum sticks and their wrappers W' are directly released from the magazine. If a 20 label wrapper is to be applied, as shown in Fig. 27, two of such side wrapping folding elements are employed, one at each end of the reciprocable carriage, the latter to receive the gum stick after it is fully wrapped 25 and to apply the label wrapper L thereto. The carriage has a relatively short reciprocating movement and the swinging or otherwise movable stop element co-operates with the carriage when in full action to arrest 30 a series of gum sticks in space, to allow the carriage to move forwardly relatively thereto, so that when the stop element is released from the gum sticks and the carriage moves rearwardly the gum sticks 35 bodily move with the carriage mechanism and are wrapped by the folding mechanism. After inner and label wrappers are applied to the gum sticks the finally wrapped sticks are released into a space to receive a number 40 of sticks to make up a desired group, and the groups may be removed for further wrapping, if desired.

All of the above referred to mechanisms, excepting the magazine for the gum sticks, 45 the mechanism for cutting and feeding inner wrappers, the stop elements for arresting the gum sticks in space while the carriage wrapping slot passes thereover, are carried by and reciprocate with the carriage. 50 The carriage is designated as a whole by 17 and is mounted to reciprocate by means hereinafter described on a suitable frame 10, in which is journaled a shaft 11 (Figs. 1, 7, and 18). Fixed to the shaft is an eccentric 12 for oscillating the stick magazine, designated as a whole by 13, a grooved eccentric 14 for raising and lowering the stop element, designated as a whole by 15, 55 into and out of the plane of the gum stick path, and a third eccentric 16 for reciprocating the carriage 17. A drive shaft 18 is arranged longitudinally of the machine and transversely to the shaft 11 and is rotatably mounted in suitable bearings in the 60 machine frame, and may be driven by any

suitable motor. Said shafts 11 and 18 are provided with meshing spiral gears 19 and 20, respectively, (Figs. 3 and 5) through the medium of which the counter shaft is driven by the drive shaft. The drive shaft 70 18 is also provided at the rear end of the machine (Fig. 1) with a pinion 21 which meshes with a gear 22 arranged on a short horizontal shaft 24 parallel to shaft 18. Said latter shaft 24 is provided with a beveled pinion 25 which meshes with a beveled gear 26 arranged upon a shaft 27 which, in the complete wrapping and sealing machine, is adapted to actuate mechanism for transferring a group of wrapped gum sticks to 80 a single sealing mechanism which may receive groups from a plurality of sidewise disposed wrapping mechanisms.

In the structure illustrated, two individual wrapping mechanisms are located 85 side by side and in parallel relation to each other, and are supported on the same carriage, one at each side thereof, though one or more than two of said mechanisms may be employed. When two wrapping mechanisms are employed, as shown, the sealing mechanisms can be located in rear thereof and in a vertical plane between the vertical planes of the wrapping mechanisms. The total sealing mechanism is not here shown, 90 only sufficient to show its relation in the combination. This arrangement is an advantageous one inasmuch as the speed of the sealing mechanism is relatively slower than the wrapping mechanism because the 95 sealing mechanism handles groups of gums, while the wrapping mechanism handles individual gum sticks; therefore, it becomes possible to operate two wrapping mechanisms serving a single sealing mechanism at 100 desirably low speed, while maintaining the output of the machine high. Both wrapping mechanisms, including the gum and label magazine and wrapper folding and cutting mechanisms, as well as the stop elements and actuating means therefor, are substantially alike and the description of one unitary wrapping mechanism will apply to the other. In the following description, therefore, the parts will be referred to in 110 the singular except where the context indicates otherwise.

The magazine 13 in which the gum sticks to be wrapped are stacked is pivotally mounted upon a shaft 28 carried by the 115 upper ends of standards 29 that rise from and are secured to the bed of the machine frame. The standards 29 also carry reels 30 for rolls of inner wrapping material W such as wax paper, tin foil, or the like. The 120 wrapping material extends in a web in front of the magazine and is intermittently fed from the roll and has a portion thereof severed from the web by a suitable cutting mechanism to provide an inner wrapper W' 125 130

each time the carriage moves forwardly and the lower part of the magazine is oscillated in the opposite direction or rearwardly by means hereinafter mentioned. The magazine 13 is swung on the shaft 28 by means of a link 31 connected to its lower end and the link is in turn hinged to the upper end of a lever 32 which is pivoted upon a shaft 33, the opposite or forked lower end 10 33¹ of the lever being in engagement with the eccentric 12. Thus, as the shaft 11 is rotated, the magazine 13 will be caused to swing, and its swinging movement co-operates with the folding and wrapper feed elements to cause the separate sticks of gum to be successively released from the magazine and positioned so as to permit the holders of the folding elements 34, hereinafter specifically described, to pass over a released 15 gum stick and a wrapper which has been cut from the strip W and deposited across the path of the sticks, it being understood that the said holders of the wrapping elements pass over the released gum sticks 20 and wrappers, by reason of the movement of the carriage, as distinguished from the gum sticks being forced into the folding element.

The lowermost end of the magazine 13 is 30 open except for the laterally spaced supporting fingers 35 (Figs. 19 and 20) that are fixed to the lower end of the magazine; the stack of gum sticks resting, when the magazine is swung rearwardly, on said rearwardly projecting spaced fingers 35, and at other times, or when the magazine is swung forwardly, on parallel fixed striping bars 37. The uppermost faces of the stack supporting fingers 35 are spaced at 35 their rear ends from the lowermost rear wall edge of the magazine to provide a release slot 36 through which the lowermost stick of the stack of gum is served or released to the element 34 by the stationary bars 37, as best shown in Fig. 20. The upper faces 40 of the fixed bars 37 are higher than the magazine fingers 35 a distance approximately the thickness of a gum stick so that when the gum stack is supported on the magazine fingers 35 at the rearmost limit of movement of the swinging magazine, as shown in Fig. 19, and at a time when the magazine is swung rearwardly, the lowermost gum stick is below the plane of the upper faces 45 of said bars 37 and in the plane of the blunt rear ends of said bars.

By reason of the horizontal plane relation of the fingers 35 and bars 37 which support the gum at respectively different times, and 50 of the fact that the fingers 35 move with the magazine and the bars 37 are fixed and have blunt ends, the rear ends of the fixed bars constitute stops that limit the forward movement of the lowermost gum stick so that 55 at the forwardmost throw of the magazine

the lowermost stick is released from the magazine (Fig. 20), in position to have one of the holders of folding element pass thereover.

By referring to Fig. 6, it will be seen that 70 the fixed bars 37 are arranged between the two center and the side fingers 35 on the magazine, and reference to Fig. 19 indicates that the upper edges of the fixed bars project above the upper edge faces of said fingers 35 75 sufficiently to permit them to engage and serve or release the lowermost gum stick through the slot 36 to the element 34 and also to slide underneath the next succeeding gum stick and prevent it from dropping out 80 of the magazine onto the fingers 35. The lowermost stick of gum is retained in the planes of the upper edges of the fingers 35 during a portion of the movement of the magazine and until the forwardmost edge 85 of the bottom gum stick in the magazine assumes the relative position shown in Fig. 20, in which the lowermost gum stick is deposited upon the upper faces of the bars 37 90 so as to be in position to be served or released to one of the holders of the element 34 upon the next forward movement of the magazine, it being observed that the rear ends of the fixed bars constitute in their assemblage, 95 relatively to the movable fingers 35, stop shoulders to limit the forward movement of the lowermost stick of gum during the forward swing of the magazine so that the lower gum stick is arrested as the magazine continues forwardly away from said lower 100 stick of gum to leave the latter in position to permit one of the holders of element 34 to pass thereover. The fingers 35 are formed on a cross member 39 of the magazine casting 38, the central part of which is spaced from 105 the magazine to provide a space which permits of access to the lowermost gum sticks at the lower end of the magazine, should this access at any time be found necessary or desirable.

110 A paper cutting and feed mechanism is provided to feed the web W from the roll 30 of waterproofed material and cut pieces or lengths W¹ to form the inner wrapper for the gum sticks. This paper feeding mechanism is actuated upon swinging movement of the magazine by a ratchet and pawl mechanism and the cutting mechanism is also actuated through movement of the magazine, all as hereinafter described.

115 The paper feed mechanism embraces a pair of rollers 40 and 41 (Figs. 1, 5, and 18), between which the web of wrapping material is passed. The rollers are carried by a bracket 42 which is mounted upon the 120 swinging magazine 13. The shaft 40' of the roller 40 co-operates with a dog and ratchet mechanism 43 in which the ratchet is fixed to shaft of roller 40, the dog being loosely connected to one end of a link 44, the oppo- 125 130

site end of which link is loosely connected or hinged at 44' (Figs. 1 and 4) to the stationary bracket 29. As the lower end of the magazine is swung rearwardly the dog and 5 ratchet mechanism is actuated to advance or feed the web of wrapping material downwardly between cutting blades 45 and 46 (Figs. 1, 4, 5, 18, 20) and the wrappers W' are arrested by the wrapper supporting 10 fingers 47 arranged below the gum stack supporting fingers 35, 35 of the magazine, and which support the cut wrappers W' between the magazine and the folding element 34. Said supporting fingers are mounted on the 15 lower ends of arms 48, which latter extend up along sides of and are pivoted at their ends to the magazine by the studs 49 to swing independently of the magazine, so that the wrapper supporting fingers are 20 movable relatively to the magazine and carriage.

The actuation of the magazine to swing the lower end causes the knife 45 to move toward and from knife 46 to sever the wrappers from the strip W so that that portion thereof between the knives and the fingers 47 constitute an individual wrapper W' which is subsequently folded about the gum stick as the upper holder of the rotatable 5 element 34 passes over the gum sticks. The wrapper web is fed downwardly between said knives by the rollers 40, 41 after the magazine structure reaches its forwardmost position and begins to swing rearwardly. 10 The wrapper supports 47 are lightly pressed against the folding element 34 (Fig. 19) during a part of the rearward swing of the magazine and for a distance during the forward swing thereof, due to action of spring 15 51, and during the latter part of the forward movement of the magazine a stop 48" acts on bar 48 to swing stop 47 free of folding element 34 (Fig. 1) to allow the folding element to rotate on its axis without clashing with the wrapper support.

Thus it will readily be seen that the separate gum sticks are successively released from the magazine by reason of the lower end of the magazine passing forwardly away 50 from the folding element 34 at the time the gum sticks are resting on the fingers 35 with the bottom-most gum in rear of and abutting against the blunt ends of releasing bars 37 and at a time when the carriage and the 55 side folding element approach or reach their forwardmost positions, so that the holders of the folding element pass over a gum stick and its wrapper, as shown in Fig. 19, and that the inner wrapper W' is fed across the 60 plane of each bottom stick as it is released from the magazine. Also said wrapper is severed from the web W prior to the release of the gum stick from the magazine into one of the holders of the folding element 34, 65 and that as the gum stick is so released

from the magazine to the holder the wrapper is folded partially about the gum stick (Fig. 20). The folding element, 34, has both a rotatable and a bodily reciprocable motion, the latter imparted to it because 70 mounted on and moving with the carriage, and the former imparted to it through the medium of an intermittently actuating ratchet mechanism hereinafter described. The rotative movement of the folding element 75 34 carries the side wrapped gum stick to a position where it can be successively operated upon by the coöperation of the reciprocal carriage and the relatively swingable stop element 15 as the gum stick and 80 wrapper move rearwardly to complete the side and end folding of the inner wrapper about the stick, as will hereinafter appear.

The swinging stop element 15, through the coöperation of which and the reciprocable 85 carriage the gums and wrappers are carried past the end flap folding devices (best shown in Fig. 14) consists of parallel arms 53 connected by cross members giving thereto a general ladder effect. The uppermost faces 90 of said bars are provided with longitudinally spaced notches 55 formed between longitudinally spaced upstanding lugs 56 which coöperate with the stripper bars 37 and the folding element 34 to release the 95 bottom gums from the magazine and to relieve said folding element of a partially wrapped gum stick and cause the gum stick to intermittently change its position in the carriage at a time when the partially 100 wrapped gum stick is stationary in space and the carriage is moving forwardly there-over, said partially wrapped gum stick to be subsequently and intermittently shifted rearwardly relatively to the machine 105 through movement of the carriage and bodily with the carriage by reason of being confined therein during the rearward movement of said carriage. The gum sticks and inner wrappers are acted upon to effect 110 further folding (Figs. 21, 22, and 23) when passing a fixed folding mechanism which comprises, in part, a plate designated by the numeral 58 (Fig. 11) and shown in place in the machine in Figs. 18 and 24 to 115 complete the side and end folds of the inner wrapper about the gum sticks in a manner to be hereinafter described.

The lugged stop element 15 is pivoted to the stationary frame 10 by a pin 58^a (Figs. 7, 120 16, 17, and 18) at the front end of the machine, and has an actuating arm 59 pivotally connected at its upper end to the stop element at 60, the stop element having hubs 15¹, 15² (Fig. 14) to receive the pivot and 125 connecting pins. The lower end of the arm 59 (Fig. 18) is forked to straddle the drive shaft 11, and said arm is also provided with a stud having an anti-friction roller 61 which travels in a closed cam 130

groove 62 of the cam 14 before referred to, the cam groove having an eccentric portion to actuate said stop element. Thus, as the shaft 11 is rotated the stop element 15 will have imparted to it once during each rotation of the shaft 11 an up and down swinging movement about the pin 58^a or toward and away from the carriage. This movement is so timed with respect to the travel of the carriage and the side folding element 34 which reciprocates with the carriage that during the forward travel of the carriage, or its movement toward the magazine, said bar 15 will be raised to bring its lugs into the path of the gum sticks in the folding element 34 and in the carriage, and with its notches partially embracing the partially wrapped gum sticks so as to arrest or stop the movement of the partially wrapped gum sticks in space and allow the carriage, in its forward movement, to travel over the same, thus repositioning the gum sticks longitudinally of or toward the rear end of the carriage. The stop element recedes or is lowered away from the carriage during the travel of the carriage in the reverse or rearward direction so that the partially wrapped gum sticks travel bodily rearwardly with the carriage and are thus advanced in space toward the rear end of the machine. Thus it will be seen that the partially wrapped gum sticks are advanced during the rearward travel of the carriage solely by their contact with the carriage and are repositioned in said carriage, by being held fixed in space by the lugs 56 of the stop element, when the carriage travels forward. Thus, a very short stroke or travel of the carriage is utilized to move the gum sticks through the carriage. Moreover, it will be observed that the lugs on the stop element can be brought very gently against the partially wrapped gum sticks inasmuch as the lugs are raised into the plane of the path of the gum sticks with said lugs closely adjacent to the forward edges of said sticks. Therefore, the starting of the gum sticks to relatively new positions in the carriage as the gum sticks travel through the machine is effected with little or no impact push of the lugs of the stop element. The danger of breaking hard gum sticks or crushing soft gum sticks is greatly lessened or entirely eliminated. The machine may, therefore, in so far as affected by these conditions, be safely run at high speed.

As before stated, the folding element 34 reciprocates with the carriage, and in addition thereto has a rotary movement on its axis in a clockwise direction, imparted to it when the carriage is moved rearwardly (Figs. 21, 22 and 23), by a suitable ratchet mechanism, herein described, it being held non-rotative with respect to the carriage when latter moves forwardly. During the

rearward and rotative movement of the element 34, the stop element 15 is in its lowermost position, as shown in Fig. 21, and thus said stop element does not interfere with the rotation of the said folding element. The relative extreme positions which the folding element 34 may assume in the reciprocation of the carriage are shown in Figs. 20 and 22. In the extreme forward position of said folding element, it is in front of the forwardmost lugs 56 of the stop element 15 and the gum stick theretofore contained in the lowermost holder of the rotatable folding element 34 is at this time located in rear of said lug when said stop element is in its upper position (Fig. 20), and the partially wrapped gum stick is released from the folding element 34 and is passed through the folding mechanism 58 after the stop element swings downwardly and when the carriage again moves rearwardly.

By referring to Figs. 7 to 9 inclusive, and 19 to 23 inclusive, the operation of the folding element 34 and its co-operation with the magazine and the stop element 15 will be clearly understood.

In Fig. 7 is illustrated the actuating means whereby the folding element 34 is rotated at the time the carriage 17 is moved rearwardly and the stop element is in its lower position, as shown in Fig. 21. Said actuating means includes a pair of meshing gears 62, and 63, the gear 62 being fixedly mounted (as pinned) upon a shaft 64 which carries the folding elements 34 at both sides of the carriage. These folding elements in the complete machine are arranged upon the opposite ends of said shaft 64, and said shaft is mounted in pairs of bearings 64¹ which are parts of the reciprocating carriage, as shown best in Figs. 1 and 8. Thus when the gear 62 is rotated in the direction shown by the arrow in Fig. 7, the shaft 64 together with the pair of folding elements 34 will also be correspondingly rotated toward the rear of the machine (Fig. 21).

The lower gear 63 has an extension or hub which is pinned to a short shaft 66 parallel to and below shaft 64 and is rockingly mounted in bearings 66¹ on the carriage. (Fig. 8.) A toothed ratchet 65 is formed on or carried by said hub, and a pitman or link 69 is loosely secured at one end to a rocking arm 67 loose on the shaft 66 (Figs. 7 and 8), and has its opposite end loosely secured to a stationary part or depending lug 70 of the frame 10. A pawl 68 is pivoted to the rocking or oscillating arm 67 and is spring urged to engage the teeth of the ratchet 65. Therefore, as the carriage is reciprocated rearwardly by the eccentric 16 the element 34 will be rotated a quarter turn in a clockwise direction (Fig. 21), and will place one of the holders 71, 72, 73 or 74 of said element 34 so as to present the upper holder to the lower

end of the magazine 13 (Fig. 19) to cause the holder to pass over a stick of gum which has been released from the magazine, together with a wrapper, as shown in Fig. 20, and will also locate the lower holder of the folding element 34 and the gum stick therein in front of the first pair of lugs 56, as shown in Figs. 20 and 23. The stop element 15 is then swung downwardly as the carriage is reciprocated rearwardly and during its rearward reciprocation the folding element 34 is rotated ninety degrees, as indicated in Fig. 21, the final position of the element 34 after rotation being illustrated in Fig. 22. During a rotation of the folding element 34 from the position shown in Figs. 20 and 23, or where the folding element is in front of the forward pair of lugs 56, it has been turned so that a theretofore vertical holder thereof is at the lowermost part of the folding element, and with said folding element in rear of said first pair of lugs 56 (Fig. 22) and in the first recess 55 or stop element 15. Therefore, upon the next forward movement of the carriage, as denoted by the arrow in Fig. 22, and by reason of the fact that the stop element 15 is then in its upper position and with its first pair of lugs 56 in engagement with the lowermost gum stick, said stick will be held from movement in space, but is relatively displaced in the carriage while carriage moves forwardly. When the partially wrapped gum stick is thus relatively displaced in the carriage, though held fixed in space, the horizontal portion of the fixed wrapper element 58 will pass over the intermediate portion of the partially wrapped gum stick and side fold it, as will be evident from a comparison of Figs. 6, 9 and 22. After this operation has occurred the stop element is again lowered and the carriage is again reciprocated rearwardly and bodily carries the gum sticks rearwardly in space, and during such rearward movement the folding element 34 is turned ninety degrees in a direction to assume the position shown in Fig. 22. When the carriage again reaches its rearward limit of movement the stop element 15 is again raised, and as the partially wrapped gum stick has been caused to assume a relatively different position with respect to the carriage it will be engaged by a next rearward pair of lugs 56 of the stop element 15 and occupy the next rearward recess 55 therein. As the carriage moves forwardly again the wrapping element constituted by the elements 34 and 58 will be forced over the partially wrapped gum sticks that are in the lowermost holder of the folding element 34, and at the end of the said forwardmost movement, the upper holder of the folding element 34 is forced over a gum stick just released from the magazine, together with its wrapper.

The successive operations of the mechanisms described serve to progressively release the gum sticks from the lower end of the stack in the lower end of the magazine, to cause the holder of the folding element to pass over the released gum stick when in the position shown by Fig. 20 by reason of the forward travel of the carriage relatively to the fixed bars 37, (the holder receiving also the wrapper W' and folding it partially about the gum stick,) to turn the rotative element 34 so as to bring a partially wrapped gum stick in line with a folding slot or way 58¹ between the folding plate 58 and a superjacent part of the carriage and fold the final side fold of the wrapper W about the said stick, and to effect progressive movement of the said wrapped gum sticks through said slot or way and past end flap folding means hereinafter described until the gum sticks are fully side and end wrapped and ready for delivery to a label applying mechanism (if such be employed) and embracing in part the intermittently rotative element 76 shown in Figs. 17 and 18, and hereinafter more fully described. From an examination of said Figs. 17 and 18, and from what has been said about the co-operative action of the reciprocable carriage and the stop element whose lugs 56 are alternatively moved into and out of the plane of the gum stick path, it will be apparent that the gum sticks and their wrappers, after leaving the intermittently rotative folding element will be progressively shifted in the carriage, due to the arrest of the gum sticks in space when the carriage moves forwardly, and due to the bodily rearward movement of the gum sticks with the carriage when the carriage travels rearwardly. In the machine shown the wrapped gum sticks are released from the rear end of the folding slot or way 58¹ by the rearmost pair of lugs 56, when the carriage moves forwardly, to the lower holder of the rotative element 76 (Fig. 18) and hereinafter to be more fully described. The wrapped gum sticks with the labels applied are progressively released into a space in which a group of a desired number of sticks can be accumulated, which groups may thereafter be handled, as groups, and may be wrapped in a sealing wrapper, if desired, the sealed packages to be thereafter labeled when desired.

Referring now more specifically to the structural details of some of the elements whose functions have been hereinbefore outlined, it will be noted that the element heretofore generally designated by 34 is designed so as to produce two heads 78, constituting the ends of the folding element, and in each head are formed four holders 71 to 74 disposed about the four sides of a rectangle, together with means between the heads to engage the partially wrapped gum sticks to hold said sticks in place while in the folding

130

element, as best shown in Figs. 1, 3, 6, 8 and 9. As shown in Fig. 3 there are two of these folding elements and two magazines 13. The holders 71 to 74, inclusive, of each head 5 are open at their inner ends and are spaced apart so that the partially wrapped gum sticks engage said holders and span the space between them. The holders 71 to 74, inclusive, are also open at their sides to receive and relieve the gum sticks. Said folding element further comprises means between the holders to properly hold the partially wrapped gum sticks within the holders. Said means, as herein shown, consists 15 of a rectangular block 79 the various faces of which are in alignment with the bottoms of the holders 71 to 74, inclusive, and these faces are each provided with inclined elevations 80 whose lower planes are at the forward sides of the faces to engage the under faces of the partially wrapped gum sticks and to frictionally hold the latter in place (Figs. 8 and 9) as they are passed from the magazine 13 into the folding element 34 and 20 also while this element is rotated. These inwardly opening holders 71 to 74, inclusive, for the ends of the partially wrapped gum sticks may be formed in any suitable manner. As herein shown, the shaft on each side 25 of the machine is provided with a pair of rectangular enlargements 81, the innermost ends of which are spaced from the rectangular head 78 to provide therebetween and around the shaft 64 clearance spaces 82 to 30 receive the lugs 56 of the stop element 15 when the latter is raised so that said lugs may engage the edge of a partially wrapped gum stick, and also to permit the folding element 34 to move with the carriage and to 35 turn on its axis without interference with said lugs. The outermost ends of these rectangular enlargements 81 are formed with shouldered portions 83 to which are secured the outer ends of the inwardly projecting 40 plates 84, 84, thus spacing the parts 84 and 81 to provide the holders 71 to 74, inclusive. The plates 84 terminate adjacent to the innermost ends of the enlargements 81 and each said plate has one edge (its rear edge 45 50 relatively to its rotative movement) beveled as shown at 85 to facilitate the laying down of the last side fold of the inner wrapper before the wrapped gum stick is released into the folding slot or way 58¹ between the 55 plate 58 and the carriage frame.

As before stated the uppermost one of these holders of said folding element 34 is so arranged with respect to the release end of the magazine 13, that when the carriage 60 together with the said folding element 34 is moved forwardly a stick of gum is released into the uppermost pocket, and as the severed wrapper W' is interposed between the said folding element 34 and the 65 stack of gum sticks in the magazine, said

wrapper will be partially wrapped around said gum stick which is released from the magazine as it is inserted into the uppermost holder as most clearly shown in Fig. 20. Upon the next rearward movement of 70 the carriage the element 34 is given a quarter turn in clockwise direction (Fig. 21). This will locate the holder which was previously uppermost in a vertical position as shown in Fig. 22, and bring an empty holder 75 in line to receive the next gum stick and wrapper from the magazine when the carriage again moves forwardly. Thereafter the carriage is reciprocated rearwardly and the folding element 34 is again rotated to 80 permit the gum stick and wrapper which was just previously retained in a vertical position to be brought to the lowermost part of folding element 34, as shown in Fig. 22, so that it is just in rear of the 85 first pair of lugs 56 of the stop element 15. When the carriage again moves forwardly, carrying with it said folding element 34, the partially wrapped gum stick is held fixed in space, but by reason of the carriage movement said gum stick changes its position relatively to the carriage so as to cause the partially wrapped gum stick to pass into the folding slot 58¹ beneath the folding plate 58. During the subsequent reciprocations 90 of the carriage and collaborative elevations and depressions of the stop element the gum sticks are fully side and end wrapped in the inner wrapper and are finally released with intercepted labels to the label wrapper element 76. By reference to Fig. 20 it will be seen that three sides of a gum stick are wrapped in the wrapper W' as the gum stick and wrapper are released into the upper holder of the folding element 34 and 100 that the trailing edge of the wrapper is applied over the gum sticks as the latter are released from the lower holder of the folding element 34 to the final wrapper slot 58¹, the latter being provided with means 105 to fold the extended ends of the wrapper inwardly over the side wrapped stick.

This wrapping mechanism hereinbefore designated as a whole by 58 by which the last side fold and the two end folds are 115 laid, embraces a flat plate 88, one at each side of the machine, and flanking oblique folding elements 87 so arranged that they will engage the opposite end flaps w¹ of the inner wrapper as the partially wrapped gum 120 stick changes its position in the carriage and causes said end flaps to fold upwardly and assume the position shown in Fig. 24. The lowermost parts of said beveled and flap folding elements 87 are in a plane below the lower wall of the folding slot or way 58¹, or the lower face of the plate 88, and their shorter forward edges extend slightly beyond the forward edge of said plate 88. The plate 88 is substantially the 130

- length of the gum stick at its forwardmost edge and the oblique folding elements are spaced such distances from the lateral edge of the plate 88 as to form forwardly opening slots 89 which are parallel with each other for a distance rearwardly from the front edge of said plate 88, and said slots converge relatively to each other in their parts within the body of the plate 88 a suitable distance rearwardly from the forward edge of said plate 88. The members on which said oblique end flap folding elements are formed, and which may be integral with the carriage 17 are thus spaced from each other a distance slightly greater than the length of the gum sticks. It will thus be seen that when a partially wrapped gum stick, held stationary in place by the stop element 15, is passed over by the forward edge of 88, the oblique folding elements 87 which are in the path of the end flaps of the inner wrapper, will fold said end flaps upwardly in the manner shown in Fig. 24 so as to cause said end flaps to be guided into said converging grooves 89 and thereby cause said end flaps to be folded downwardly over the side folded package as it is caused to shift its position in the carriage during the forward travel of the latter, as best shown in Figs. 30 and 25. In the forward movement of the folding elements 58, comprising the parts thus described, the said end flaps wipe over the inner vertical faces 87¹ of the elements and the curved portions 90 of the converging slots 89, so that said end flaps will be held closely confined during the turning or folding movement thereof, until they are finally laid on the side folds by passing beneath the portions 91 of the plate 88. Subsequently, the separately wrapped sticks may be passed directly to the labeling mechanism, hereinafter to be described.
- The plate 88 is removably held in place with respect to the carriage by holding means which includes a lever 92 (Figs. 7, 10, 16 and 17) which is pivoted at 93 and extends across the plate and is engaged by a hold down latch 93¹ also carried by the carriage. Said lever 92 carries a spring actuated detent 94 which engages a center socket 94¹ in a cross bar 95 (Fig. 11), the ends of which are provided with extensions 96, 96 that enter slots formed in standards 96¹ which rise from the carriage at the sides thereof. The bar 95 is formed with downwardly opening notches 95¹ which register with the converging end flap folder slots 89 (Figs. 10 and 11). The construction described provides means whereby the plate 88 may be readily removed in the event of the machine clogging in the folding slot or way beneath the same, such removal being effected by releasing the latch 93¹ and swinging the lever 92 upwardly about the pivot 93; and also provides means whereby the removable plate may be held reliably in place. The said plate 88 is supported on inwardly extending ledges 97 of the carriage 17 (Figs. 10 and 25), lying flat thereon with wide supporting faces and held in clamped position by the lever 92; and the upper faces of the ledges or arms 97 are rabbeted at 100 to afford spaces for the ends of the wrapped gum sticks.
- The next step in the operation of the machine, as shown, is the application to the wrapped gum stick of an outer or label wrapper L. Such label wrapper can be fed from a chute 102 in which are deposited a number of suitably dimensioned label wrappers, these wrappers being fed through the chute by any suitable pressure means, (not necessary to show) and being applied across the path of the gum sticks as they are released into the folding device 76 whereby the label wrappers are applied to the individual previously wrapped sticks, the label being furnished with an adhesive material while being delivered from the magazine 101 to said folding device.
- The chute 102 is pivotally mounted at its lower end 103 to the reciprocating carriage 17. Said chute has an arm or link 104 loosely connected to its upper end and said link is connected to the pivot 28 of the gum stick magazine 13. Thus as the carriage is reciprocated the lowermost end of the chute 102 swings with it and the parts are thereby held in proper working relation. Said chute and the coöperating construction is duplicated, as is the principal mechanism previously explained. Therefore, the explanation of one will answer for both.
- A feed roller 105 is journaled in the carriage below the chute 102, which latter is open at its lower end, and said roller has a portion of its periphery covered with a friction material 106 such as rubber. Said roller bears against the lowermost label wrapper, and consequently, as the roller is rotated the wrappers will be intermittently fed from the chute each time the friction portion thereof contacts with the lowermost wrapper. The wrapper is fed downwardly past guide fingers 107 and into the path of the wrapped gum stick, as the sticks are released from the rearmost end of the side and end wrapping mechanism described. The lowermost end of each wrapper is fed between glue applying rollers 108 and upstanding fingers 109 of a wrapper stop which is carried by the glue pot 110 (Figs. 17 and 18).
- Referring now more particularly to Fig. 12 it will be seen that a plurality of these glue applying rollers are employed and also that they project rearwardly beyond the face of the glue pot through suitable slots therein. Therefore, the lowermost portions of the label wrappers L will have applied thereto small area glue patches l, as shown in 130

Fig. 27. The rollers 108 are supplied with paste or glue through the medium of a transfer roller 111 which contacts with a roller 112 that rotates partially submerged in the 5 paste or glue in the pot 110.

The said paste applying mechanism and the intermittently rotative folding elements 76, before referred to, and which apply the label wrappers to the individual wrapped gum 10 sticks, is shown and operated as follows: The label wrapper feed roll is fixed to a shaft 134 that is rotatively mounted in the carriage 17. The shafts 116 and 134 carry a spur gear 115 and a pinion 135, respectively, 15 so ratioed as to drive the label wrapper stripper roll 105 at a suitably high speed as compared to the speed of the folding element 76. 117 designates a shaft mounted in the carriage on which rotates a spur gear 20 114 that meshes with the spur gear 115. A ratchet wheel 118 is secured to the shaft 117 and a spring urged pawl 119 is hinged to a spring arm 120, which latter is rockingly mounted on the shaft 117. Said arm has 25 loosely secured to it a link 121 which extends forwardly and is loosely secured to a stationary portion of the machine at 122.

In the construction shown, the pawl 120 engages the ratchet 118 below the same, as 30 distinguished from the arrangement of the pawl 68 relatively to its ratchet 65, before described. (Fig. 7.) Therefore, when the carriage travels forwardly, the pawls 68, 119 ride idly over their ratchets 65, 118 so that 35 during the forward travel of the carriage, neither of the folding elements 34 or 76 rotate; but when the carriage travels rearwardly both said folding elements are partially rotatable but in opposite directions, 40 as shown in Fig. 17.

The said folding element 76 receives the wrapped gum stick from the slot or way 58' when one of the holders 136 thereof is in line with said slot or way (Fig. 16) and the folding element 76 turns in the direction indicated by the arrow in Fig. 17, so as to bring a wrapped gum stick and its partially wrapped label wrapper from beneath into a pocket to receive a plurality of wrapped 45 and labeled gum sticks in rear of said rotating folding element, as will be hereinafter described, and supported on and movable with the carriage.

The multi-faced paste applying roll 108 50 is driven from the spur gear 114 of the driving mechanism for the intermittently rotative folding element 76 through the medium of a spur pinion 123 on shaft 124 (Figs. 7 and 10) that is rotatively mounted in suitable bearings in the carriage, which said gear 123 meshes with a pinion 125, shown as formed within the perimeter of a short shaft 126 also rotatively mounted in suitable bearings in the carriage. The paste 55 pot 110 is shown as removably seated on and

supported by a platform constituting part of the carriage 17 and a screw stud 110' (Figs. 1, 12, and 17) constitutes means to removably fix the paste pot on the carriage. The removability of the paste pot permits it 70 to be detached for cleaning purposes and for charging the same, and it becomes desirable that the driving mechanism for the paste applying rolls be constructed to be readily separable so that the paste pot may 75 be detached by merely removing the screw 110' and sliding the paste pot outwardly. Such a detachable driving gear is shown best in Figs. 1, 10, and 12 and it is made as follows: 80

Fixed to the end of the shaft 126 and exterior to an upright web 172 is a disk 127 that has an eccentric stud 127' which is adapted to engage a like eccentric stud 128' on a disk 128 which is fixed to the shaft 129 85 of the multiple faced paste applying roller 168 before referred to. Said shaft 129 is coaxial with shaft 126 and the driving studs 127', 128' endwise overlap and are at equal radial distances from the axes of the shafts 90 126 and 129, so that rotation of the shaft 129 serves through said studs to cause rotation of the multiple faced paste applying roller 108. The transfer and submerged rollers 111 and 112, respectively, are driven 95 mutually from the shaft 129 through the gears 130, 131, and 132 on the several shafts of the rollers in the manner best shown in Figs. 1, 10, and 12. The disk 128 is cut away, as shown in Fig. 12, to facilitate assembling the paste pot and the driving gears and for readily removing the paste pot. 100

The folding mechanism designated in part by 76 is turned through one quarter of a rotation in each reciprocation of the carriage, while the label wrapper stripper roll 105 requires to turn a complete rotation during such period. The gear 135 of the shaft 134 of the feed roller is, therefore, a comparatively small gear to mesh with the larger 110 gear 115; these gears being so ratioed that a quarter turn of the gear 115 imparts a full turn to the gear 135 and consequently rotates the feed roller sufficiently to move the label sheet from the chute 102 in rear of the 115 paste applying rollers 108 and into the path of a wrapped gum stick as it is released from the folding slot device. The gearing to drive the paste applying roller 108 is also so proportioned as to drive said roller relatively faster than the gear 114. 120

When a label wrapper L assumes the position shown in Fig. 18, it is in the path of a wrapped gum stick as it is released from the paper folding slot or way 58', and as the 125 rotatable element 76 travels with the carriage, this stick with its inner wrapper will be inserted into one of the pocket holders 136 thereof, as the carriage moves forward due to the fact that the gum stick is held 130

fixed in space while the holder of the element 76 is moving forwardly thereon. At this time the label wrapper is tucked into the holder and is wrapped partially about the 5 gum stick, leaving the gummed fold l' thereof projecting downwardly so as to be wiped against the multi-faces of the paste applying roller 108. The label is assisted in this action by the fingers 109 which cause the 10 end of the paper nearest the rollers to brush against the same upon the rotation of the elements 76 in the direction shown in Fig. 17 or an anti-clockwise direction, and is brought to rest in the position shown in Fig. 15 18, with one holder in the plane of the wrapping slot or way 58' and the other angularly offset holder in position to release a partially labeled wrapped gum stick to a grouping mechanism, indicated as a whole 20 by 138 (Fig. 18), which is supported on and is movable with the carriage. The label folding element 76 comprises two head-like portions which are spaced apart along the shaft 116, each head having four holders 25 136 that open inwardly or toward each other and are angularly spaced ninety degrees apart. The bottoms of said holders are spaced apart along the axis of the shaft 116 a distance equal to the length of a 30 wrapped gum stick, being practically end defined by the flanges 140 and coincide generally with the depressed faces 100 of the carriage ledges, as best shown in Fig. 6. The completely wrapped and labeled gum 35 sticks are released from the folding element 76 when the carriage moves forward, by means of fingers 137 that extend downwardly and forwardly from a cross bar 137^a that is fixed to or made part of the frame 40 (Figs. 16, 17, and 18); and the lower ends of said fingers extend into the space between the heads of the folding element, as best shown in Fig. 6, so that said lower ends of the fingers may engage the forward edges of 45 the wrapped and labeled gum sticks when in the position shown in Fig. 18. Thus, when the carriage moves forwardly, the fingers 137 serve to hold the gum sticks in space so that the accumulating mechanism 138 moves 50 over the gum sticks thus released from said folding element. The construction of said folding element 76 is such that the hollow holder arms of the heads are first at one side and then the other side of the terminals 55 of the stop arms 137 and, inasmuch as the folding element rotates in a counter clockwise direction, the wrapped and labeled gum sticks are, so to speak, caused to be passed upwardly and behind the fingers 137 when 60 the carriage is moving backwardly so that the gum sticks will be arrested or stopped when the carriage again moves forwardly and released from the rearmost holders of 65 said rotating element in position for the grouping mechanism 138 to pass thereover at a time when the forwardmost holder is in position to receive an inner wrapped gum stick that has just been released from the wrapping slot or way 58', and when a gum stick is being released from the magazine 70 into the folding element 34. During the rotation of the element 76, a gum stick which has previously been released into one of its holders, finally assumes a horizontal position in front of the 75 grouping mechanism 138, between it and the stripper fingers 137 (Fig. 18). Therefore, when the carriage moves forwardly, the uppermost stick of gum is released from the element 76 and is passed over by the 80 yielding roller 140', which is arranged between the ends of the gum sticks and are opposed to the yielding elements 141 and 142 arranged to lightly act upon the opposite ends of the gum sticks. As the 85 sticks of gum are passed between these elements, the trailing portion l' of the label wrapper L is folded under the stick of gum and the paste previously applied to this trailing portion causes it to be pasted to 90 the previously side folded portion l'' of the label wrapper. The yieldable roller 140' is carried by one end of a spring urged arm 143 arranged upon a pivot 144, the opposite ends of which are mounted in arms 95 145 which, in turn, are rigidly fastened to a shaft 146 which is mounted in the standards 147 which are secured to and supported on the reciprocating carriage 17. A second shaft 148 is journaled between 100 said standards 147 and is arranged below the shaft 146 and in rear of the yieldable roller 140'. It carries a plurality of rollers 149, 150, and 151 which are fixed to the shaft, the latter of which are arranged rearwardly of the yieldable elements 141 and 142 (Figs. 13 and 17, respectively) the former being positioned in substantial alignment with the yieldable roller 140'. This shaft 148 is arranged above a yieldable 110 table 153 onto which the individually wrapped and labeled gums are passed and retained until a prescribed number in a bundle have been accumulated. This table 153 is mounted upon the rear face of a web 115 154 which forms part of the reciprocable carriage. It is yieldably sustained in a boss 155 which is bored to receive a stem 156 extending downwardly from the table 153 and a coiled spring 157 reacts between a 120 shoulder provided on the stem and the bottom of the bore to yieldingly tend to tilt the table upwardly. The uppermost end of this spindle carries the table 153 which is of a length substantially equal to the distance between outer faces of the rollers 150 and 151, and consequently will support the sticks of gum throughout their lengths. This yieldable table bears against the face of the 125 wall 154, and thus it is retained in its proper 130

relative position as it vertically moves with relation to said wall. The rearmost face of the table is provided with a pair of recesses 159 which are sufficient in depth to permit 5 the introduction of grasping fingers which grasp and remove a prescribed number of pieces of gum from the accumulating mechanism.

It will be observed that the two side wrapping mechanisms described are practically 10 duplicates of each other, embracing, in part, the magazines or article holders 13, with the means for releasing the gum stick therefor, the inner wrapper feeding and cutting 15 mechanism, the folding units 34, the wrapper plates 88, the label feed, the rear folding element 76, and the grouping mechanism 138, and that said mechanisms are bilaterally disposed and balanced on a carriage 20 which is suitably shaped to support the operative parts and bearings for the various shafts. This construction also make it practicable and efficient to locate the driving shafts at one end of the machine and the 25 means for reciprocating the carriage and rotating the folding elements 34 and 76 by mechanism located compactly between the side portions of the carriage.

The upright walls 154 of the carriage are 30 connected together by a horizontal plate 160 having the outwardly extending flanges 161 which ride in the guideways 162 of the main frame (Figs. 13 and 15). The carriage has a depending bracket 163, to which is 35 connected the pitmen 164 which is connected with and driven by the eccentric before described. This causes the reciprocation of all of the mechanism secured to the carriage, when the machine is driven.

From the foregoing explanation of the structure, it will be seen that separate gum sticks are consecutively released from the magazine 13 together with the inner wrappers W' and that the holders of the wrapping element 34 successively pass over and receive the gum sticks and partly wrap the wrappers about the sticks and further that the quarter turn of the holder element 34 in each rearward reciprocation of the carriage successively brings the gum sticks and wrappers into the plane of the folding slot or way in the carriage, and that the gum sticks and wrappers are completely side folded and end folded as they progress 55 rearwardly through the machine. It will also be observed that the gum sticks and their wrappers change their positions relatively to the carriage when the carriage travels forwardly, due to the fact that said 60 gum sticks and wrappers are at such time held fixed in space by the lugs 56 of the stop elements 15 and that when the carriage travels rearwardly, with the stop elements withdrawn from the plane of the gum sticks, 65 the gum sticks and their wrappers are dis-

placed rearwardly in space by the simple act of bodily traveling with the carriage. It will be furthermore observed that the gum sticks and their wrappers progress through the machine in relatively small increments 70 of movement and inasmuch as each stage of travel is relatively small and the lugs 56 of the stop elements are brought gently against the edges of the gum sticks, crushing or breaking of the gums is absent. Moreover, the inner wrapped gum sticks are released from the rear end of the slot or way 58' into the holders of the folder element 76 by which the label wrapper is applied to the gum, and the labeled and wrapped gum is 80 likewise released from the holders of the element 76 by the fingers 137 and deposited directly into the bundle mechanism 138, to be therefrom removed for further treatment, as to a central sealing mechanism. 85

It will furthermore be observed that the movements of the gum sticks are in direct lines except for the rotating elements 34 and 76 and that progressive movement of the gum sticks and their wrappers by a positively driven plunger is eliminated, with the attendant destructive effect of such a positively driven plunger. It is furthermore observed that the construction described adapts itself to a plural wrapping mechanism and a single intermediate sealing mechanism, whereby the mechanism is capable of large output without driving the machine parts at objectionably high speeds. Thus, a large continuous production is assured with a minimum loss in breakage of the articles being wrapped. 95 100

While I have herein shown and described one embodiment of the invention, it is obvious that changes and modifications may be resorted to without departure from the spirit of the invention as defined by the appended claims. 105

I claim as my invention:

1. A wrapping machine comprising a 110 movable carriage into which an article and its wrapper are placed, and means for advancing said article and wrapper relatively to and through the carriage to wrap the wrapper about the article, said means including an element which engages said article and wrapper and is stationary while in engagement. 115

2. A wrapping machine comprising a reciprocating wrapping element travelable 120 horizontally in a straight path only, with fixed guides to confine its traveling movement and adapted to pass over the article and wrapper in one direction of its movement and means for holding said article in 125 space during said direction of travel of the wrapping element, and arranged to permit the article and wrapper to be moved in a straight path with the wrapping element in the other direction of travel thereof.

3. A wrapping machine comprising a reciprocable carriage in which an article and its wrapper are placed, folding means to engage the wrapper and wrap it about the article, and means to hold the article and wrapper in space in one direction of movement of the carriage and to engage the wrapper with the folding means, said means being released from the article and wrapper in the opposite direction of movement of the latter. 70
4. A wrapping machine comprising a reciprocable carriage in which an article and its wrapper are placed, folding means movable with the carriage, and means to arrest said article in space when the carriage moves in one direction to engage the folding means with the wrapper, said arresting means being inoperative during the opposite movement of the carriage. 75
5. A wrapping machine comprising a reciprocable carriage into which the article to be wrapped and its wrapper are placed, and means movable into and out of the path of travel of the articles to engage and hold the article within said carriage and free from movement in space during one direction of movement of the carriage, the carriage in the other direction of movement thereof advancing the article and its wrapper in space. 80
6. In a machine of the class described the combination of a reciprocable carriage adapted to travel over an article and wrapper delivered thereto, wrapper folding means, and means movable into and out of and through the path of travel of the article and its wrapper for moving said article relatively to the carriage, and holding said article and wrapper stationary when in said path to cause the article and wrapper to move into engagement with said folding means. 85
7. A wrapping machine comprising a reciprocable slotted carriage and wrapping mechanism carried thereby, feeding means at one end of the carriage to feed an article and its wrapper to the slot of the carriage, and means to hold said article and wrapper within said carriage and fixed in space while the carriage reciprocates toward said feeding means, and to release the article and wrapper to permit them to move with the carriage while the carriage reciprocates away from said feeding means. 90
8. A wrapping machine comprising a reciprocable carriage and wrapping mechanism carried thereby, feeding means at one end of the carriage to feed an article and its wrapper to the carriage, and means movable toward and into the path of said article in the carriage in a direction at a right angle to the path of said article. 95
9. A wrapping machine comprising an article holder, a reciprocable wrapping element adapted to pass over an article and its wrapper, means to release an article from said holder, other means to feed a wrapper across the plane of the released article, whereby both article and wrapper are released to said reciprocating wrapper element, and means to hold the article and its wrapper in said carriage and stationary in space when the wrapping element is moving toward said article holder, constructed to release the article and wrapper when said element moves in the opposite direction. 100
10. A wrapping machine comprising a reciprocable wrapping element adapted to pass over an article and wrapper, a swinging article holder, with means to swing it, means cooperating with the holder to release an article and wrapper to said wrapping element when the latter moves toward the holder, and a stop element movable into and out of the path of said article and wrapper constructed to engage the latter when the wrapping element is moving toward said holder. 105
11. A wrapping machine comprising a reciprocable wrapping element for supporting an article to be wrapped and a single multi-staged element having projections movable into and out of the path of the article and wrapper for intermittently arresting movement of the article and wrapper and to thereby progressively shift said article relatively to said wrapping element. 110
12. A wrapping machine comprising a reciprocable wrapping element for supporting an article to be wrapped and a single multi-staged element having projections movable into and out of the path of the article and wrapper for arresting movement of the article and wrapper and to thereby progressively shift said article relatively to said wrapping element, said reciprocating wrapping element bodily carrying the article and its wrapper through the machine. 115
13. A wrapping machine comprising a wrapping element to receive the articles and wrapper to be wrapped therearound, and means for moving said articles through the machine, said means including a multi-staged element having spaced projections to intermittently engage said articles and which is stationary while in engagement therewith. 120
14. A wrapping machine comprising a reciprocable wrapping element, with means whereby it is passed over an article and a wrapper to be wrapped therearound, and means for moving said article and wrapper through the wrapping element, said means including a stop element constructed to successively engage said article to cause it to be intermittently shifted relatively to said wrapping element. 125
15. A wrapping machine comprising an oscillatory holder for the article, a wrapping element into which an article and its wrap- 130

- per is released by movement of said holder, and means for progressively moving said article and wrapper through said wrapping element, said means including a member 5 which is movable into and out of the path of said article and wrapper and held stationary when engaged with said article and its wrapper.
16. A wrapping machine comprising a reciprocal support for the article to be wrapped and having a wrapping mechanism, and a member coöperating with said support to move the article and its wrapper with relation to the support through the 10 machine and in contact with the wrapping mechanism, said member being a plurality of means to successively engage the article and being stationary when so engaged with the article.
17. A wrapping machine comprising a reciprocating carriage adapted to pass over an article and wrapper, and means for holding said article and wrapper in space during one direction of travel of the carriage and 15 permitting the article to be moved bodily with the carriage in the other direction of travel thereof, said carriage embracing a rotative folding element movable with and supported thereon and into which the wrapper and article is passed through movement of said carriage.
18. A wrapping machine comprising a reciprocating wrapping element having a way through which an article and its wrapper are adapted to intermittently pass to fold the wrapper around the article, and a swingable stop member movable into and out of the path of the article to hold the article fixed in space in one direction of movement 20 of said element and to permit the article to bodily move with said element in the other direction of movement thereof.
19. A wrapping machine comprising a swingable article holder, with means to co-operate therewith to successively release the lowermost article of a stack of articles, a reciprocating wrapping element into which an article released from said holder and its wrapper is placed, and a stop element embracing a series of longitudinally spaced lugs which are movable into and out of the path of the article and wrapper.
20. A wrapping machine comprising a swingable article holder, with means to co-operate therewith to successively release the lowermost article of a stack of articles, a reciprocating wrapping element into which an article, released from said holder, and its wrapper is placed, and a swinging stop element provided with a series of longitudinally spaced lugs swingable toward and from the wrapping element, with said lugs engaging the article and wrapper when said wrapping element reciprocates toward said holder.
21. A wrapping machine comprising wrapping mechanism, a swinging magazine having a lateral discharge opening, members fixed and movable with said magazine, respectively, to support a stack of articles 70 in the magazine, the fixed members supporting the stack in one position of the magazine, and the members movable with the magazine supporting the stack in another position thereof, said fixed members acting 75 in the latter position to release the bottommost article of the stack to said wrapping mechanism.
22. A wrapping machine comprising a swinging magazine having a lateral discharge opening, members fixed and movable with said magazine, respectively, to support a stack of articles in the magazine, the fixed members supporting the stack in one position of the magazine, and the members movable with the magazine supporting the stack in another position thereof, said fixed members acting in the latter position to release the bottommost article of the stack, and a wrapping mechanism in position to receive 80 an article so released, together with a wrapper fed across the path of the released article.
23. A wrapping machine comprising a reciprocal wrapping mechanism, a swinging magazine, with means to swing it, said magazine being provided at its release end with a finger movable therewith and spaced from the magazine to provide a release opening and adapted to support a stack of 85 articles in one position of the magazine, and a member fixed relatively to the magazine to support the stack in another position of the magazine, and coöperating with said finger to release the articles successively from 90 said stack.
24. A wrapping machine comprising a reciprocal wrapping mechanism, a swinging magazine, with means to swing it, said magazine being provided at its release end with a finger movable therewith and spaced from the magazine to provide a release opening and adapted to support a stack of articles 95 in one position of the magazine, and a member fixed relatively to the magazine to support the stack in another position of the magazine, the supporting face of the latter member being above the plane of the supporting face of the finger whereby, when the magazine is swung in one direction, the articles drop on said finger in rear of the fixed member and are thereby released from the magazine.
25. A wrapping machine comprising a reciprocal wrapping mechanism, a swinging magazine, with means to swing it, said magazine being provided at its release end with a finger movable therewith and spaced from the magazine to provide a release opening and adapted to support a stack of arti- 100

- cles in one position of the magazine, and a member fixed relatively to the magazine to support the stack in another position of the magazine, the supporting face of the latter member being above the plane of the supporting face of the finger whereby when the magazine is swung in one direction, the articles drop on said finger in rear of the fixed member and are thereby released from the magazine, said wrapping mechanism including a reciprocating element which is movable toward the release end of the magazine when the latter is in a position to support the bottommost article on said finger in rear of said fixed member. 26. A wrapping machine comprising a reciprocable wrapping mechanism, a swinging magazine, with means to swing it, said magazine being provided at its release end with a finger movable therewith and spaced from the magazine to provide a release opening and adapted to support a stack of articles in one position of the magazine, and a member fixed relatively to the magazine to support the stack in another position of the magazine, the supporting face of the latter member being above the plane of the supporting face of the finger whereby, when the magazine is swung in one direction, the articles drop on said finger in rear of the fixed member and are thereby released from the magazine, said wrapping mechanism including a reciprocating element which is movable toward the release end of the magazine when the latter is in a position to support the bottommost article on said finger in rear of said member, a single power device, and operative connections between said power device and the wrapping mechanism and magazine constructed to cause the magazine to, first, swing toward the wrapping mechanism, and to thereafter swing forwardly during the forward reciprocation of the wrapping mechanism but with a progressively slower swing. 27. A wrapping machine comprising a frame, a swinging magazine having a lower lateral release opening and provided with fingers movable therewith to support a stack of articles in the magazine in one position of the magazine, fixed members beneath the magazine to support said stack in another position of the magazine, and formed with shoulders to release the articles from the magazine during the swinging movement of the latter, and a wrapping mechanism adapted to pass over a released article and an interposed wrapper during relative movements of the wrapping mechanism and magazine. 28. A wrapping machine comprising a frame, a swinging magazine having a lower lateral release opening and provided with fingers movable therewith to support a stack of articles in the magazine in one position of the magazine, members fixed to the frame to support said stack in another position of the magazine, and formed with shoulders to release the articles from the magazine during the swinging movement of the latter, a wrapping element reciprocable toward and from said magazine to pass over articles, released from the magazine, and an interposed wrapper, and means to advance an article and wrapper through the wrapping element, embracing a stop element movable into and out of the path of the article and wrapper to hold the latter fixed in space during one direction of movement of the wrapping element and to permit said article to bodily move with said wrapping element during the opposite movement of the latter. 29. A wrapping machine comprising a reciprocable wrapping element, including a rotary wrapping element supported by and movable with the reciprocable element, an article holder having a release opening and swingable toward and from said reciprocable wrapping element, and movable with the wrapping element for a portion of its swing, means fixed relatively to said article holder to support at certain times a stack of articles therein, combined with means to successively release the articles from the holder during one direction of swing of the latter into the reciprocable wrapping element, and means to advance the article and wrapper, embracing a stop element having projections that move into and out of the path of the reciprocating wrapping element and are immovable when engaged with the article and wrapper. 30. In a wrapping machine, a swingable article holder having a lateral discharge opening at its swinging end, a finger movable with said holder for supporting a stack of articles in one position of the holder, a fixed member raised slightly above the finger for supporting said articles in another position of the holder, said fixed member having a shoulder in rear of which the bottommost article drops when the holder swings in one direction to effect release of the article from the holder when swinging toward said fixed member, and wrapping mechanism to receive the released article from the holder, together with a wrapper therefor. 31. In a wrapping machine, a swinging article holder having a lateral discharge opening at its swinging end, a finger movable with said holder for supporting a stack of articles in one position of the holder, a fixed member raised slightly above the finger for supporting said articles in another position of the holder, said fixed member having a shoulder in rear of which the bottommost article drops when the holder swings in one direction to effect release of the article from the magazine when swing-

- ing toward said fixed member, and wrapping mechanism to receive the released article from the magazine together with a wrapper fed in its path, said wrapping mechanism embracing a carriage reciprocable toward and from said fixed member, and a stop element movable into and out of the path of the article and wrapper, embracing longitudinally spaced projections to hold the article and wrapper fixed in space during movement of the carriage toward said fixed member while allowing the wrapper and article to move with the carriage in the other direction of movement thereof.
- 15 32. A wrapping machine comprising a slotted reciprocable wrapping mechanism, means to successively release articles and wrappers in position for the wrapping mechanism to pass thereover, and means to hold said articles and wrappers fixed in space while the wrapping mechanism moves toward the releasing means, and to permit the articles and wrappers to move bodily with the wrapping mechanism when the latter is moved away from said releasing means.
- 20 33. A wrapping machine comprising a holder element in which articles to be wrapped are contained, wrapping mechanism, means for positioning a wrapper across said wrapping means, and means for successively releasing said articles from said element, together with wrappers fed in their path, embracing means to impart to and fro relative movement of the holder element and said wrapping mechanism.
- 25 34. A wrapping machine comprising a holder element in which articles to be wrapped are contained, a wrapping mechanism embracing a reciprocating element, and a rotative folding element supported thereon and movable therewith, means to feed a wrapper across said folding element, said rotative element and holder element being relatively movable, whereby an article may be released from the holder element to said rotative element, together with a wrapper fed across its path, and means whereby a partially wrapped article is released from said folding element to other wrapper means.
- 30 35. In a machine of the character described, the combination of a reciprocable carriage having means for supporting an article to be wrapped, and means to move the article in the carriage through the machine, embracing a member swingable toward and from the carriage and constructed to engage and hold the article fixed in space in said carriage in one direction of movement of the carriage.
- 35 36. In a machine of the character described, the combination of a reciprocable carriage having means for supporting an article and an oscillatory member for engaging the article and holding the same against movement in space within the carriage in one direction of movement of the latter and to be released from engagement in the other direction of movement of the carriage to effect a movement of the article through the machine relatively to the carriage.
- 40 37. In a machine of the character described, the combination of a reciprocable carriage having means for supporting an article and wrapper, and means to deliver an article partially folded in said wrapper to said carrier, a member movable for engaging the article and wrapper in said carriage when the carrier travels toward the article and wrapper delivery means and for holding the article against movement during such carriage travel, and means whereby said member is movable out of engagement with said article and wrapper when the carriage travels in the other direction to permit the article to travel in and with the carriage to effect a movement of the article through the machine.
- 45 38. A wrapping machine comprising wrapping means, including a reciprocable support for wrapper and the article to be wrapped and means for advancing an article and wrapper through the machine in engagement with the wrapping means constructed to engage and move the article a prescribed distance relatively to the support when the support is moved in one direction and said article is held stationary and said means being movable to permit the article to be moved with the support when the support is moved in the opposite direction.
- 50 39. A wrapping machine comprising wrapping means, including a reciprocable support to receive wrapper and the articles to be wrapped, and means for moving the articles and wrappers relatively to the support and in engagement with the wrapping means, said means including an element having a plurality of means for successively engaging the articles to hold them stationary when the support moves a prescribed distance in one direction and to release the articles when the support moves in the other direction.
- 55 40. A wrapping machine comprising wrapping means, including a reciprocable support to receive wrappers and the articles to be wrapped and means for moving the articles and wrappers relatively to the support and in engagement with the wrapping means, said means including an element having a plurality of stop projections for successively engaging the articles to move them a predetermined distance relatively to the support when the support is moved in one direction, and said means being movable to permit the articles to be moved with the support when the support is moved in the opposite direction.
- 60 41. A wrapping machine comprising

wrapping means, a reciprocable slotted support to receive wrappers and the articles to be wrapped, and means for moving the articles and wrappers relatively to the reciprocable support and in engagement with the wrapping means, said means including an element to successively engage the articles and cause them to be moved a prescribed distance relatively to the support upon the movement of the support in one direction and to be moved with the support when the latter moves in the other direction.

42. A wrapping machine including an element constructed to receive an article to be wrapped, said element being mounted to reciprocate and to be intermittently rotated to receiving and discharging positions, and means engageable with an article contained in said element for relieving said element of the article when said element is reciprocated.

43. A wrapping machine including a rotatable and reciprocable element constructed to be rotated from receiving to discharging position, wrapping means into which an article is passed from said element, and means for passing said article from said element to the wrapping means upon the reciprocation of said element.

44. A wrapping machine including a rotatable and reciprocal element constructed to be rotated and reciprocated from receiving to discharging position, means into which said article is passed from said element and stationary means for causing said article to be passed from said element to said means upon the reciprocation of said element.

45. A wrapping machine comprising an article holding element, wrapping means for receiving at one end an article from said element, together with an inner wrapper, an outer label applying device co-operatively arranged with respect to the other end of the wrapping element, and a single element constructed to effect progressive movement of the article and wrapper from the holder element to the outer label applying device.

46. In a machine of the character described, the combination of a reciprocal carriage having means for supporting an article and a member for engaging the article and holding the same against movement to effect a movement of the article relatively to the carriage, said member being constructed to intermittently engage the article to progressively shift the same with relation to the carriage.

47. In a wrapping machine, a magazine for the articles to be wrapped, a wrapping mechanism, means whereby the articles are successively released from the magazine to the wrapping mechanism through relative movement of said wrapping mechanism and said magazine, and a paper cutter and wrapper feed mechanism operated by movement of one of the said relatively movable parts.

48. In a wrapping machine, a magazine for the articles to be wrapped, a wrapping mechanism, means whereby the articles are successively released from the magazine to the wrapping mechanism through relative movement of said wrapping mechanism and said magazine, and a paper cutter and wrapper feed mechanism, embracing a fixed and a movable knife between which a wrapper web is passed, the movable knife being fixed to and operated by movement of the movable part.

49. A wrapping machine comprising a wrapping mechanism, a swinging magazine for a stack of articles to be wrapped from which the bottommost articles are successively released to the wrapping mechanism, with means to swing the magazine toward and from the wrapping mechanism, and a wrapper support below the article releasing plane of the magazine and carried by said magazine.

50. A wrapping machine comprising a wrapping mechanism, a swinging magazine for a stack of articles to be wrapped from which the bottommost articles are successively released to the wrapping mechanism, with means to swing the magazine toward and from the wrapping mechanism, and a wrapper support below the article releasing plane of the magazine and carried by said magazine, said wrapper support being movable relatively to said magazine.

51. A wrapping machine comprising a wrapping mechanism, a swinging magazine for a stack of articles to be wrapped from which the bottommost articles are successively released to the wrapping mechanism, with means to swing the magazine toward and from the wrapping mechanism, and a wrapper support below the article releasing plane of the magazine and carried by said magazine, said wrapper support being movable relatively to the magazine and adapted in the rearmost movement of the magazine to yieldingly engage said wrapping mechanism.

52. A wrapping machine comprising a wrapping mechanism, a swinging magazine for a stack of articles to be wrapped from which the bottommost articles are successively released to the wrapping mechanism, with means to swing the magazine toward and from the wrapping mechanism, a wrapper support below the article releasing plane of the magazine and carried by said magazine, said wrapper support being movable relatively to said magazine, and means to raise and lower said wrapper support relatively to said magazine.

53. A wrapping machine comprising a wrapping mechanism, a swinging magazine for a stack of articles to be wrapped from which the bottommost articles are successively released to the wrapping mechanism,

with means to swing the magazine toward and from the wrapping mechanism, and an arm swingably mounted at its upper end on the magazine structure and formed at its lower end to constitute a wrapper support to sustain a wrapper between the releasing plane of the magazine and said wrapping mechanism.

54. A wrapping machine comprising a wrapping mechanism, a swinging magazine for a stack of articles to be wrapped from which the bottommost articles are successively released to the wrapping mechanism, with means to swing the magazine toward and from the wrapping mechanism, an arm swingably mounted at its upper end on the magazine structure and formed at its lower end to constitute a wrapper support to sustain a wrapper between the releasing plane of the magazine and said wrapping mechanism, and spring means engaging said arm to normally press said wrapper support rearwardly.

55. In a wrapping machine, the combination with a wrapping mechanism, of a swinging magazine having an article releasing opening, a paper cutting mechanism embracing relatively movable knives, between which the paper is fed, one of which is attached to the magazine, a wrapper support movably supported on said magazine below said releasing opening, and spring means mutually acting on said support and the movable knife to maintain them in operative position.

56. In a wrapping machine, the combination with a wrapping mechanism, of a swinging magazine having an article releasing opening, a paper cutting mechanism embracing relatively movable knives, between which the paper is fed, one of which is attached to the magazine, a wrapper support movably supported on said magazine below said releasing opening, and a spring acting on said blade and said support to press the movable on the fixed knife and to yieldingly extend the wrapper support toward the wrapping mechanism.

57. In a wrapping machine, the combination with a frame and a wrapping mechanism supported thereon, of a magazine swingingly supported on said frame and having an article releasing opening, a paper cutter mechanism comprising a U-shaped knife fixed to the frame having its cutting edge in the closed part of the U and a knife normally pressed in the arms of the fixed knife and fixed to the swinging magazine, whereby it is movable toward and from the cutting edge of the fixed knife.

58. In a wrapping machine, the combination with a frame and a wrapping mechanism supported thereon, of a magazine swingingly supported on said frame and having an article releasing opening, a paper cutter mechanism comprising a U-shaped knife fixed to

the frame having its cutting edge in the closed part of the U, a knife normally pressed in the arms of the fixed knife and fixed to the swinging magazine, whereby it is movable toward and from the cutting edge of the fixed knife, and yielding means to press the movable knife against said arms in a plane transverse to the direction of travel of the movable knife.

59. In a wrapping machine, the combination with a frame and a wrapping mechanism supported thereon, of a magazine swingingly supported on said frame and having an article releasing opening, a paper cutter mechanism comprising a U-shaped knife fixed to the frame having its cutting edge on the closed part of the U, an arm hinged to swing on said magazine and yieldingly pressed toward the plane of the fixed knife and a second knife carried by said arm to co-operate with the fixed knife.

60. In a wrapping machine, a wrapping element, a swinging article holding magazine from which articles are released to said wrapping element, and wrapper cutting means, embracing a fixed knife and a co-operating knife connected to and movable with said swinging magazine.

61. In a wrapping machine, a wrapping element, a swinging article holding magazine from which articles are released to said wrapping element, and wrapper cutting means, embracing a fixed knife and a co-operating knife connected to and movable with said swinging magazine, said movable knife being movable in a straight path, and the co-operating edges of said knives having angular shearing relation.

62. A wrapping machine comprising a frame, a carriage mounted to reciprocate thereon and formed with a downwardly opening longitudinal recess, wrapping means supported on and movable with said carriage, means at the front end of the carriage to release an article and a wrapper to the carriage, and a long swing stop element swingable through said recess into the path of, and to hold an article and wrapper in the carriage throughout one direction of reciprocation of the carriage and to move out of the path of said article in the opposite reciprocation of the carriage.

63. A wrapping machine comprising a frame, a carriage mounted to reciprocate thereon and formed with a downwardly opening longitudinal recess, wrapping means supported on and movable with said carriage, means at the front end of the carriage to release an article and a wrapper to the carriage, and a long swing stop element swingable through said recess into the path of, and to hold an article and wrapper in the carriage throughout one direction of reciprocation of the carriage and to move out of the path of said article in the opposite

reciprocation of the carriage, said stop element having a plurality of longitudinally spaced lugs to simultaneously coöperate with a number of articles and wrappers while in 5 said carriage.

64. A wrapping machine comprising a frame, a carriage mounted to reciprocate thereon and formed with a downwardly opening longitudinal recess that opens to 10 a wrapping slot in the carriage, wrapping means supported on and movable with said carriage, including a rotatable folding element on the forward end of the carriage rotative on an axis above said wrapping 15 slot and having a series of angularly disposed holders to which articles and wrappers are successively released and by rotation of which element they are successively delivered to said slot, and an element having stop 20 members movable through said recess into the path of the articles and wrappers when the latter occupy said slot and said folding element acting to hold the articles and wrappers fixed relatively to the frame in one 25 direction of its reciprocation, while permitting them to move with the carriage in the other direction of its reciprocation.

65. A wrapping machine comprising a frame, a carriage mounted to reciprocate 30 thereon and formed with a downwardly opening longitudinal recess opening to a slot, wrapping means supported on and movable with said carriage, means at the front end of the carriage to release an article and 35 a wrapper to the carriage, a long swing stop element swingable through said recess into said slot to hold the article and wrapper therein throughout one direction of reciprocation of the carriage and to move out 40 of the path of said article in the opposite reciprocation of the carriage, a rotative shaft mounted in the frame, and timed operating means on the shaft to impart mutually coöperative movements to the carriage 45 and holding means, for the purpose set forth.

66. A wrapping machine comprising a frame, a carriage mounted to reciprocate thereon and formed with a downwardly 50 opening longitudinal recess opening to a slot, wrapping means supported on and movable with said carriage, wrapper feed means to feed a wrapper across said slot along swing stop element swingable through 55 said recess into said slot to hold the article and wrapper therein throughout one direction of reciprocation of the carriage and to move out of the path of said articles in the opposite reciprocation of the carriage, an 60 article holder mounted on said frame to swing toward and from said carriage and coöperating in its movement to release articles successively from the holder, together with their wrappers delivered by wrapper 65 feed means across said slot to said wrapping

means in one direction of reciprocation of the carriage, while permitting them to move with the carriage in the other direction of its reciprocation.

67. A wrapping machine comprising a frame, a carriage mounted to reciprocate thereon and formed with a downwardly opening longitudinal recess opening to a wrapping slot, wrapping means supported on and movable with said carriage, means at the front end of the carriage to release an article and a wrapper to said slot, a long swing stop element swingable through said recess into said slot to hold the article and wrapper therein throughout one direction of reciprocation of the carriage and to move out of the path of said article in the opposite reciprocation of the carriage, a rotative shaft mounted in the frame, eccentrics on 75 said shaft, and links having studs riding on said eccentrics and connected, respectively, with said carriage and stop element.

68. A wrapping machine comprising a frame, a carriage mounted to reciprocate thereon and formed with a downwardly opening longitudinal recess opening to a slot, wrapping means supported on and movable with said carriage, feed means to feed a wrapper across said slot an article holder mounted on said frame to swing toward and from said carriage and coöperating in its movement to release articles successively from the holder together with their wrappers to said wrapping means, and a long swing stop element swingable through 90 said recess into said slot to hold the article and wrapper therein throughout one direction of reciprocation of the carriage and to move out of the path of said article in the opposite reciprocation of the carriage.

69. A wrapping machine comprising a frame, a carriage reciprocable therein and having a wrapping slot, a rotative folding element supported on and movable with said carriage and having a plurality of holders 100 to receive articles and their wrappers and rotative from receiving position to releasing position, the latter in the plane of said slot, and stop means movable into the plane of the articles and adapted, when stationary, 115 to engage the articles during one direction of movement of the carriage and to move out of said plane during the opposite direction of movement of said carriage.

70. A wrapping machine comprising a frame, a carriage reciprocable therein and having a wrapping slot, a rotative folding element supported on and movable with said carriage and having a plurality of holders 120 to receive articles and their wrappers and rotative from receiving position to releasing position, the latter in the plane of said slot, and stop means movable into the plane of the articles and adapted, when stationary, 125 to engage the articles during one direction 130

of movement of the carriage and to move out of said plane during the opposite direction of movement of said carriage, said wrapping slot being bounded at its top by a plate that has converging wrapper end flap folding slots that open at the front edge of said plate.

71. A wrapping machine comprising a frame, a carriage, reciprocable therein and having a wrapping slot, a rotative folding element supported on and movable with said carriage and having a plurality of holders to receive articles and their wrappers and rotative from receiving position to releasing position, the latter in the plane of said slot, stop means movable into the plane of the articles and adapted, when stationary, to engage the articles during one direction of movement of the carriage and to move out of said plane during the opposite direction of movement of said carriage, said wrapping slot being bounded at its top by a plate that has converging wrapper end flap folding slots that open at the front edge of said plate, and fixed oblique faced members at the entrance of said end flap folding slots to guide the ends of the wrapper into said latter slots.

72. A wrapping machine comprising a frame, a carriage, reciprocable therein and having a wrapping slot, a rotative folding element supported on and movable with said carriage and having a plurality of holders to receive articles and their wrappers and rotative from receiving position to releasing position, the latter in the plane of said slot, stop means movable into the plane of the articles and adapted, when stationary, to engage the articles during one direction of movement of the carriage and to move out of said plane during the opposite direction of movement of said carriage, said wrapping slot being bounded at its top by a plate that has converging wrapper end flap folding slots that open at the front edge of said plate, and fixed oblique faced members at the entrance of said end flap folding slots to guide the ends of the wrapper into said latter slots, with means to clamp said plate on said carriage.

73. A wrapping machine comprising a frame, a carriage mounted to reciprocate thereon and having a wrapper side folding slot, with means to release an article and wrapper to the front end of said slot, said slot being bounded by a top plate having converging wrapper end flap folding slots which open toward the receiving end of the carriage folding slot, and stop means movable into and out of the plane of the articles in the carriage folding slot for contact, when stationary, with said articles and wrappers in said latter slot.

74. A wrapping machine comprising a frame, a carriage mounted to reciprocate

thereon and having a wrapper side folding slot, with means to release an article and wrapper to the front end of said slot, said slot being bounded by a top plate having converging wrapper end flap folding slots which open toward the receiving end of the carriage folding slot, and stop means movable into and out of the plane of the articles in the carriage folding slot for contact, when stationary, with said articles and wrappers in said latter slot, said top plate being removably fitted to the carriage to permit, when removed, access to said slot, with means to detachably fix said plate to said carriage.

75. A machine for wrapping individual articles and applying a label wrapper thereto, comprising a frame, a reciprocable carriage thereon, having wrapper folding means, said means embracing a rotative multi-holder element to successively receive articles and their wrappers to partially fold the wrappers about the articles and to deliver them to other folding means of the carriage, a label folding element supported on said carriage to successively receive wrapped articles from said carriage folding means, together with label wrappers, and stop means to hold the articles and wrappers fixed in space when the carriage is traveling in one direction and to allow said articles to move with carriage when said carriage is traveling in the opposite direction.

76. A machine for wrapping individual articles and applying a label wrapper thereon, comprising a frame, a reciprocable carriage thereon, having wrapper folding means, said means embracing a rotative multi-holder element to successively receive articles and their wrappers to partially fold the wrappers about the articles and deliver them to other folding means of the carriage, a rotative multi-holder label folding element carried by said carriage to successively receive wrapped articles from said side and end folding means, together with label wrappers, stop means to hold the articles and wrappers fixed in space when the carriage is traveling in one direction and to allow said articles to move with said carriage when said carriage is traveling in the opposite direction, and means fixed to the frame to release the label wrapped articles from said label folding element.

77. A wrapping machine comprising a frame, a wrapping element reciprocable thereon, having a wrapping slot, a folding element rotatively mounted on said wrapping element and having plural holders to receive articles and wrappers and in turn to deliver them to said wrapping slot, means stationary in operative position to engage the articles when the wrapping element reciprocates in one direction, and adapted to move out of engagement with the articles

when said wrapping element reciprocates in the other direction, means to reciprocate said wrapping element, and pawl and ratchet mechanism to rotate said folding element when the carriage is reciprocated in one direction.

78. A wrapping machine comprising a frame, a wrapping element reciprocable thereon having a wrapping slot, a plural holder folding element rotatively mounted on and reciprocable with said carriage, means to reciprocate said carriage, a pawl and ratchet mechanism operable in one direction of movement of the wrapping element to intermittently rotate said folding element, and a stop element movable into said wrapping slot when the wrapping element is reciprocated in one direction, and movable away from said slot when the wrapping element reciprocates in the opposite direction.

79. A wrapping machine comprising a frame, a wrapping element reciprocable thereon having a wrapping slot, a plural holder folding element rotatively mounted on and reciprocable with said carriage means to reciprocate said carriage, a ratchet connected to said rotative folding element, a swinging member carrying a pawl to engage said ratchet, a link fixed at one end to the frame and hinged at its other end to said swinging member, and means to advance articles and wrappers through said wrapping slot.

80. A wrapping machine comprising a frame, a wrapping element reciprocable thereon having a wrapping slot, a plural holder folding element rotatively mounted on and reciprocable with said carriage, means to reciprocate said carriage, a ratchet connected to said rotative folding element, a swinging member carrying a pawl to engage said ratchet, a link fixed at one end to the frame and hinged at its other end to said swinging member, and a stop element movable into and out of said slot and stationary relatively to the reciprocable wrapping element when the latter is moved in one direction.

81. A wrapping machine comprising a frame, a carriage reciprocable thereon having a wrapping slot, a rotative plural holder supported on and movable with said wrapping element and adapted to receive articles and wrappers and partially fold them and deliver them to said folding slot, a second rotative plural holder label holding element also supported on and movable with said wrapping element and adapted to receive wrapped articles from said slot, together with labels fed into the path of the wrapped articles, pawl and ratchet mechanisms to simultaneously and intermittently turn said first folding and said label folding elements, and means to progressively advance said

articles through said slot and into said rotative label folding element.

82. A wrapping machine comprising a frame, a carriage reciprocable thereon having a wrapping slot, a rotative plural holder supported on and movable with said wrapping element and adapted to receive articles and wrappers and partially fold them and deliver them to said folding slot, a second rotative plural holder label holding element also supported on and movable with said wrapping element and adapted to receive wrapped articles from said slot, together with a label fed into the path of the wrapped article, ratchets respectively geared to said rotative folding elements, swinging members carrying pawls to respectively engage said ratchets, links connected at corresponding ends to said frame and at their other ends to said respective swinging members, and means operative during one stroke of the wrapping mechanism to displace the articles relative to said wrapping mechanism and constructed to permit said articles to freely move with the wrapping mechanism in the other stroke thereof.

83. A wrapping machine comprising a frame, a carriage reciprocable thereon having a wrapping slot, a rotative plural holder supported on and movable with said wrapping element and adapted to receive articles and wrappers and partially fold them and deliver them to said folding slot, a second rotative plural holder label holding element also supported on and movable with said wrapping element and adapted to receive wrapped articles from said slot, together with a label fed into the path of the wrapped article, ratchets respectively geared to said rotative folding elements, swinging members carrying pawls to respectively engage said ratchets, links connected at corresponding ends to said frame and at their other ends to said respective swinging members, and a swinging stop element movable toward and from said wrapping element and said first folding element to arrest said articles in space during one stroke of the wrapping mechanism, said articles being bodily movable with the wrapping element in the opposite stroke thereof.

84. A machine for wrapping individual articles and applying a label band thereto, comprising a frame, a reciprocable carriage thereon having a wrapping slot and wrapping means thereat to fold an inner wrapper about the article, a rotative multi-holder label wrapping element supported on said carriage at the rear end of said slot, and movable therewith, means to effect movement of the article through said slot and into the holders of said rotating element, including an element which engages said article and is stationary while in such engagement, and a fixed member on the frame for

releasing the wrapped and labeled articles from said label wrapper element during reciprocation of said carriage.

85. A machine for wrapping individual articles and applying label bands thereto, comprising a frame, a reciprocable carriage thereon having a wrapping slot and wrapping means thereat to fold an inner wrapper about the article, a rotative multi-holder label wrapping element supported on said carriage at the rear end of said slot and movable therewith, means to effect movement of the article through said slot and into the holder of said rotative element, including an element which engages said articles and is stationary while in such engagement, means supported on the carriage to deliver a label band across the path of a wrapped article as it is moved into a holder of the rotative element, and a fixed member on the frame and extending forwardly into the plane of a wrapped and labeled article in one of said holders to release the article therefrom during reciprocation of the carriage in one direction.

86. A machine for wrapping individual articles, comprising a frame, a reciprocable carriage thereon having a wrapping slot and wrapping means thereat to fold an inner wrapper about the article, a grouping mechanism carried by and movable with the carriage, means to advance an article and wrapper through the wrapping means, and means to successively transfer wrapped articles into the grouping mechanism.

87. A machine for wrapping individual articles and applying label bands thereto, comprising a frame, a reciprocable carriage thereon having a wrapping slot and wrapping means thereat to fold an inner wrapper about the article, a grouping mechanism carried by and movable with the carriage, means to advance an article and wrapper through the wrapping means, means to successively transfer wrapped articles into the grouping mechanism, and a label applying mechanism supported on and movable with the carriage between said wrapping mechanism and said grouping mechanism.

88. A machine for wrapping individual articles and applying label bands thereto, comprising a frame, a reciprocable carriage thereon having a wrapping slot and wrapping means thereat to fold an inner wrapper about the article, a grouping mechanism carried by and movable with the carriage, a label applying mechanism intermediate the wrapping mechanism and grouping mechanism and supported on and movable with the carriage, means for moving said articles and wrappers through the wrapping mechanism and releasing them in the label applying mechanism, including an element which engages said articles and is stationary while in such engagement, and fixed means on the

frame acting during reciprocation of the carriage to successively release the wrapped and labeled articles from the label applying mechanism to the grouping mechanism.

89. A machine for wrapping individual articles and applying label bands thereto comprising a frame, a reciprocable carriage thereon having wrapping means to inclose the articles in wrappers delivered into said mechanism with the articles, a multi-holder rotative label applying device carried by and movable with the said carriage, a label magazine loosely supported at one end from said frame and supported at its other end on said carriage, with means to deliver labels therefrom between the wrapping mechanism and said label applying device, and means to progressively advance the articles and their wrappers through the wrapping mechanism to hold the articles and wrappers in space during one direction of reciprocation of the carriage and constructed to permit the said articles to move with the carriage in the opposite direction.

90. A machine for wrapping individual articles and applying label bands thereto, comprising a frame, a reciprocable carriage thereon having wrapping means to inclose the articles in wrappers, an article holder swingably supported on said frame, with means to successively release articles therefrom, together with wrappers fed across the path thereof, to said wrapping mechanism, a label applying device carried also by and movable with said carriage, a label magazine supported at its lower end on said carriage, with means to deliver labels therefrom between said wrapping mechanism and said label applying device, a link loosely connecting the upper end of said swinging article holders, and means to progressively advance the articles and their wrappers through the wrapping mechanism, including means to hold the articles and wrappers in space during one direction of reciprocation of the carriage and constructed to permit the said articles to move with the carriage in the opposite direction thereof.

91. A wrapping machine comprising a reciprocating wrapping element, a label applying device supported on and movable with the wrapping element into which the wrapped article is released from the wrapping element, a grouping device in rear of the label applying device, also movable with the wrapping element, and means fixed relatively to the frame to release the labeled wrapped articles from the label applying device to the grouping device.

92. A wrapping machine comprising a reciprocating wrapping element, a label applying device supported on and movable with the wrapping element into which the wrapped article is released from the wrapping element, a grouping device in rear of

- the label applying device, also movable with the wrapping element, said label applying device embracing a rotative element having a plurality of angularly disposed arms, each 5 formed to provide a holder, and a finger depending from the frame and adapted to lie in front of a label wrapped article in said rotative element when the carriage is in its rearmost position, the arms of said 10 holder being also spaced longitudinally of the axis of rotation thereof, and said rotative element having means to rotate it to pass upwardly from beneath said finger.
93. A wrapping machine comprising a 15 frame, a reciprocable carriage thereon, means to feed an article thereto and inclose it within a wrapper, a labeling mechanism embracing a plural holder folding element rotatively mounted in and movable with 20 said carriage, and into which the wrapped articles from the carriage wrapping mechanism are released together with a label, a grouping mechanism movable also with the carriage, and means to release the label 25 wrapped articles from said folding element to the grouping mechanism in one direction of rotation of the carriage.
94. A wrapping machine comprising a 30 frame, a reciprocable carriage thereon, means to feed an article thereto and inclose it within a wrapper, a labeling mechanism embracing a plural holder folding element rotatively mounted in and movable with 35 said carriage, and into which the wrapped articles from the carriage wrapping mechanism are released, together with a label, a grouping mechanism movable also with the carriage, and a releasing finger fixed to said frame and depending into the path of the 40 article in the folding element when the carriage reciprocates away from said finger.
95. A wrapping machine comprising a 45 frame, a reciprocable carriage having wrapping mechanism to side and end wrap an article, embracing an initial folding element rotatively mounted at the front of the carriage to receive an article and wrapper and deliver them to the other said wrapping mechanism, a label applying mechanism rotatively mounted on the rear end of the 50 carriage and movable therewith, and means operative during reciprocal movement of the carriage to simultaneously rotate said initial folding and label applying elements.
96. A wrapping machine comprising a 55 frame, a reciprocable carriage having wrapping mechanism to side and end wrap an article, embracing an initial folding element rotatively mounted at the front of the carriage to receive an article and wrapper and deliver them to the other said wrapping mechanism, a label applying mechanism rotatively mounted on the rear end of the carriage and movable therewith, means to progressively displace the article and wrapper 60 from the rotative element through the wrapping mechanism and from the latter to the label applying mechanism, embracing means to engage and hold fixed said article during reciprocation of the carriage in one direction 70 and to permit the articles to move with the carriage in the opposite reciprocation thereof, and means operable during the latter movement of the carriage to rotate said initial folding and label applying mechanisms. 75
97. A wrapping machine comprising a frame, a reciprocable carriage having wrapping mechanism to side and end wrap an article, embracing an initial folding element rotatively mounted at the front of the carriage to receive an article and wrapper and deliver them to the other said wrapping mechanism, a label applying mechanism rotatively mounted on the rear end of the carriage and movable therewith, means to progressively displace the article and wrapper 80 from the rotative element through the wrapping mechanism and from the latter to the label applying mechanism, embracing means to engage and hold fixed said article during 85 reciprocation of the carriage in one direction and to permit the articles to move with the carriage in the opposite reciprocation thereof, and means operable during the latter movement of the carriage to rotate said initial folding and label applying mechanisms. 90
98. In a wrapping machine, a shaft provided with longitudinally spaced plural holder heads that open at their sides and at their adjacent ends, said shaft being provided between said heads with a generally rectangular enlargement having transversely oblique wrapper engaging faces. 100
99. A wrapping machine comprising reciprocable wrapping mechanism, a swinging article holder having at its swinging end a lateral release opening, said wrapping mechanism and article holder being respectively reciprocable and swingable toward each other, with means to operate them, constructed to cause the holder magazine to swing first toward the wrapping magazine and to thereafter swing in the same direction as the wrapping mechanism, but with a progressively slower swing. 110
100. A wrapping machine comprising reciprocable wrapping mechanism, a swinging article holder having at its swinging end a lateral release opening, said wrapping mechanism and article holder being respectively reciprocable and swingable toward each other, with means to operate them, constructed to cause the holder magazine to swing first toward the wrapping magazine and to thereafter swing in the same direction. 120
- 125
- 130

- tion as the wrapping mechanism, but with a means to advance the article and wrapper progressively slower swing, and relatively fixed and movable article selection means at the release end of the holder to successively release the bottommost articles from the holder.
101. A wrapping machine comprising a reciprocable wrapping element, including a rotary wrapping element supported by and movable with the reciprocable element, an article holder having a release opening and swingable toward and from said reciprocable wrapping element, and movable with the wrapping element for a portion of its swing, means fixed relatively to said article holder to support at certain times a stack of articles therein, combined with means to successively release the articles from the holder during one direction of swing of the latter into the reciprocable wrapping element, and
- 5 means to advance the article and wrapper through the wrapping mechanism.
102. A wrapping machine comprising a reciprocating wrapping element, a grouping mechanism, a label applying device supported on and movable with the wrapping element, and means fixed to the frame and operative through movement of the reciprocating wrapping element to successively release the wrapped and labeled articles from the labeling applying element to the grouping mechanism.

In witness whereof I claim the foregoing as my invention, I hereunto append my signature at Syracuse, New York, this 12th day of March, 1920.

HARRY Y. ARMSTRONG.
